UNITED STATES PATENT OFFICE.

GEORGE T. NEILL, OF DULUTH, MINNESOTA.

JOINT-FASTENING DEVICE.

SPECIFICATION forming part of Letters Patent No. 426,048, dated April 22, 1890.

Application filed October 12, 1889. Serial No. 326,901. (No model.)

To all whom it may concern:

Be it known that I, GEORGE T. NEILL, a citizen of the United States, residing at Duluth, in the county of St. Louis and State of Minnesota, have invented a new and useful 5 Joint-Fastening Device; and I do hereby declare that the following is a full, clear, and exact description of the invention, which will enable others skilled in the art to make and 10 use the same.

This invention relates to improvements in joint-fastening devices, which will be herein-after more particularly described and pointed out.

15 In the accompanying drawings, forming part of this specification, Figure 1 shows the invention applied to the end of a sound tenon and ready to be inserted in a socket. Fig. 2 is a perspective view of the device enlarged. 20 Fig. 3 is a sectional elevation showing the parts of the device in assembled position.

A is a piece of sheet metal doubled back upon itself, having the butt of a size to fit the end of a round or square tenon, and having 25 the two wings a serrated, so that the end teeth a' a' will point outwardly and pierce the top and bottom walls of a mortise or socket. The teeth a'' a'' on the sides are made to point in such a manner as also to pierce the 30 socket or mortise on the sides.

B is the rung, and C the leg, of any piece of furniture.

d d , &c., are small holes punched in the sheet of metal to form points or teeth d' on the inside, so that they can be made to pierce 35 the tenon.

The device A is to be put on the end of the tenon b and the wings bent down, as shown, and the teeth a'' a'' so fixed that they will engage the sides of the mortise b , and when 40 the tenon is forced into the mortise or socket c the points a'' a'' will pierce the sides of the socket or mortise and prevent any withdrawal of the rung.

This device is self-fastening and requires 45 no other fixture or fastening.

I claim—

A joint-fastening device formed of one piece of sheet metal doubled back upon itself, having serrations a' a'' directed outwardly to 50 hold against the top, bottom, and sides of the walls of a mortise, and the teeth or projections d' to hold against the exterior of the rung or tenon, substantially as and for the purpose described.

GEORGE T. NEILL.
